UNITED STATES PATENT OFFICE.

EDGAR B. WILLS AND LOUIS W. RECK, OF MENDOTA, ILLINOIS.

LIFTING APPLIANCE FOR VEHICLES.

1,145,729.

Specification of Letters Patent.

Patented July 6, 1915.

Application filed March 14, 1914. Serial No. 824,667.

To all whom it may concern:

Be it known that we, EDGAR B. WILLS and LOUIS W. RECK, both citizens of the United States, residing at Mendota, in the county 5 of La Salle and State of Illinois, have invented certain new and useful Improvements in Lifting Appliances for Vehicles, of which the following is a specification.

The present invention relates more particularly to an appliance designed for use with an automobile or other vehicle for the purpose of lifting the same from the ground.

The objects of the present invention are to 15 provide a device of the character specified which will be automatic in action to the extent that the parts thereof will be operated by engagement of the to-be lifted vehicle therewith; to provide a forward lifting 20 means and a rear lifting means with a connection therebetween and to provide means for adjusting the length of this connection; to provide means for adjusting the length 25 of the lifting means to vary its distance from the floor; to provide means for initially moving one of the lifting means to a partially raised position and subsequently moving both lifting means in unison to their 30 fully raised position; and to arrange the lifting means in oppositely disposed sets, each set comprising a front lifting means and a rear lifting means, and to provide 35 means for adjusting these sets to and from one another to vary the distance between the same.

Further objects of the invention are to provide means for limiting the movements of the lifting means in their up and down movements; to provide cushioning or buffer 40 means for engaging the vehicle and arresting the forward movement thereof; and to provide means for manually pulling the vehicle into operative position with respect to the lifting means.

The invention further consists in the features of construction and combination of parts hereinafter described and claimed.

In the drawings Figure 1 is a side elevation showing the lifting means in their 50 lowered position in full lines, and showing by means of dotted lines the position assumed by the parts during the initial raising movement of the front lifting means; Fig. 2 is a view similar to Fig. 1 showing 55 the lifting means fully raised; Fig. 3 is a plan view of the lifting means of the pres-

ent invention; Fig. 4 is a cross section through one of the lifting means showing the catch member for locking the lifting means in its vertical position of adjustment; 60 Fig. 5 is a section on line 5—5 of Fig. 6 looking in the direction of the arrows; Fig. 6 is a vertical section through a portion of one of the lifting means; Fig. 7 is a sectional detail of the buffer mechanism; Fig. 8 is a 65 detail partly in section showing the method of mounting the lifting means; and Fig. 9 is a cross section on line 9—9 of Fig. 8.

As stated, the appliance of the present invention is more particularly adapted for 70 use in connection with automobiles and other vehicles. It is a well known fact that the manner now practised of jacking up automobiles is a tedious and laborious one, and it is also a well known fact that tires 75 are materially damaged as a result of the machine standing upon the floor of the garage. The present invention deals with a device whereby this jacking operation may be quickly and easily performed with 80 out the necessity of any tedious and laborious manual operation in effecting the same.

Referring now to the drawings, the device, as shown in Fig. 3, consists of two sets, each similar in construction and arrangement, and each set comprises a forward jack or lifting member 10 and a rear jack or lifting member 11. The terms "front" and "rear" are used mainly for the purpose of expediting the description. 85 Both sets of lifting members are shown mounted upon a flooring or base 12, although the method of mounting the same may be varied as desired. That is, they may be attached to an independent flooring, as 90 shown, or attached directly to the flooring of the garage, or other building.

The forward lifting member consists of a body portion 11^a terminating in a head 12^a which, as will be seen from Figs. 1 and 100 2, is formed with an acting face of curvilinear nature which terminates at one end in a shoulder 13. Said lifting member is provided with a sleeve-like member 14 depending from the head, which sleeve-like 105 member telescopes upon an arm 15 which is pivoted as at 16 to a mounting or bearing plate 17. The arm 15 is provided with a series of niches 18 along one edge thereof, which niches are adapted to be engaged by 110 a finger or fingers 19 on a pivoted member 20, the latter being attached to the sleeve

14. A latch 21 is also provided which is carried by the said sleeve, and this latch serves to engage and hold the member 20 in the manner shown in Figs. 1 and 2, whereby the height of the acting face of the jack can be varied as is necessary. Its operation is obvious when the latch 21 is withdrawn, thus releasing the member 20, after which the body 11 is pulled upward until the desired height is reached.

10 A rod 22 is pivotally attached to the sleeve 14 and this rod is secured to a rod 23 by means of suitable clamping members 24. The rod 23 is pivotally attached to a lever 15 25 which, in turn, is pivotally attached to a sleeve 27 forming a part of the rear lifting member 11, and this sleeve terminates in a head 28 which, as will be seen from the drawings has an acting face which is 20 slightly curvilinear in nature, and terminates in a shoulder 29. A link 30 is secured to the head 28 and is spaced away therefrom, as shown in Fig. 3, to provide a slot in which the lever 25 travels. The sleeve 26 fits over 25 an arm 31 similar to the arm 15, and adjustment of the height of the rear jack is effected in a manner similar to that described in connection with the forward jack.

30 A buffer 32 is provided which is mounted upon a frame 33, and this buffer, which is shown more in detail in Fig. 7, consists of a barrel 34 in which slides a cup-shaped member 35 provided with an opening 36 in its closed end 37, and through this opening 35 passes a stem 38 terminating in one end in a head 39, and at its other end in a nut 40, and interposed between the rear wall 41 of the barrel 34 and the wall 37 of the cup-shaped member 35 is a spring 42. It is apparent that, as the head 39 is engaged and pushed inward, it will force the head 35 inward against the tension of the spring 42, and thus act as a buffer.

45 Each of the lifting means is provided at its lower end with trunnions 43, as shown in Figs. 3 and 8, which trunnions enter into suitable journals 44 in the bearing plates 17. A collar 45 is attached to said trunnions and is held in place by a set-screw 46. It will 50 be observed that the trunnions are reduced at their ends, the reduced portions entering the journals and the collar lying beyond the reduced portions. By referring to Fig. 8, it will be seen that the collar, when positioned, lies adjacent to the bosses 44 of the bearing plates. The collar and the bosses are each partially cut away, as shown in Figs. 8 and 9, so as to bring about what may be termed an interlocking engagement therebetween. The purpose of this interlock is to limit the swing of the trunnions back and forth so as to limit the up and down movements of the lifting means or jacks.

60 The lifting means, as previously stated, 65 may be arranged in pairs as in Fig. 3, and

the plates 17 may be slotted as at 47, and locking means 48 are arranged in said slots. The support for the buffer 32 is also slotted at 47^a to permit back and forth adjustment, and locking means 47^b are likewise provided. 70 It is obvious that the sections may be made adjustable to and from one another to vary the distance between the two sections. If it is desired to manually pull the vehicle into position to be raised, a lever 49 may be 75 utilized in conjunction with the chain attached at one end to the lever, and at the other end to the to-be-raised vehicle.

80 The operation is as follows: Assuming the parts to be in position shown in full lines in Fig. 1, and the vehicle to be approaching in the direction of the arrow, the front axle 50 of the vehicle will pass over the front lifting means, owing to the fact that the said lifting means is normally lying in a 85 plane lower than the plane of the front axle, and when the vehicle has traveled a sufficient distance said front axle will engage the lever 25 pushing the same back to the dotted position, shown in Fig. 1. This will 90 lift the front lifting means to the dotted position shown in this figure and into contact with the rear axle 51, the rear and front lifting means being then in engagement with the front and rear axles respectively, 95 but no lifting operation will have as yet taken place. Now as the vehicle continues its movement, the front axle will engage with the shoulder 29, and thus act to elevate the rear lifting means 27. This will 100 obviously move the lever 25 in unison with the rear lifting means, and through the medium of the connection between the lever and the front lifting means will move the latter lifting means and move both jacks in unison 105 into the position shown in Fig. 2, in which position the vehicle will be lifted from the floor. When the vehicle will have progressed far enough to place the lifting means in the position shown in Fig. 2, it 110 will have engaged with the buffer mechanism so that further advance movement of the vehicle is resisted by such mechanism, thus bringing the vehicle to an easy stop and relieve the lifting mechanism of undue 115 shock.

120 The operation above described can be carried out, if desired, by the driving of the automobile onto the lifting means to operate the same in the manner specified, but it may happen that the driver will not possess the required skill to control the car in the manner necessary to so drive it, and if such be the case the car can be arrested at or near the point indicated by the dotted line position of the axles, as shown in Fig. 1, and can be pulled the remainder of the way by the lever 47 in conjunction with a chain or cable, and thus manually pulled forward and into operative engagement with the lifting 125 130

means. If desired, a spring may be interposed at the point of connection between the rod 23 and the lever 25 for the purpose of expediting the return of the parts to normal position, and for relieving the connection between the jacks from undue shock or strain.

We claim:

1. In a lifting appliance of the class described, the combination of front lifting means and rear lifting means, a member arranged to be engaged by the front axle of the to-be-lifted vehicle, said member being located adjacent the rear lifting means and movable independent of said rear lifting means for the initial portion of its movement, and movable in unison with said rear lifting means for the subsequent portion of its movement, a connection between said member and the front lifting means whereby upon the initial movement of said member the front lifting means is raised and upon the subsequent movement of said member the front and rear lifting means are raised in unison, substantially as described.

2. In a lifting appliance of the class described, the combination of a front lifting means and a rear lifting means, a shiftable member on the rear lifting means, a connection between said shiftable member and front lifting means, said shiftable member being arranged to be engaged and operated by the to-be-lifted vehicle, and said member acting on its initial movement to partially raise the front lifting means, and on its subsequent movement to fully raise said front and rear lifting means in unison, substantially as described.

3. In a lifting appliance of the class described, the combination of front lifting means and rear lifting means, shiftable means adapted to be engaged by the front axle of the to-be-lifted vehicle, said means being arranged adjacent to said rear lifting means, a connection between said shiftable means and the front lifting means, said shiftable means moving independent of the rear lifting means for the initial portion of its movement and moving in unison with the rear lifting means for the subsequent portion of its movement, whereby the front lifting means is raised by the initial movement of the shiftable means, and both front and rear lifting means raised by the subsequent movement of said shiftable means, substantially as described.

4. In a lifting appliance of the class described, the combination of a front lifting means and a rear lifting means, a pivoted lever on the rear lifting means, a connection between said lever and the front lifting means, said lever being arranged to be engaged and actuated by the to-be-lifted

vehicle and to act on its initial movement to partially raise the front lifting means, and on its subsequent movement to fully raise said front and rear lifting means in unison, substantially as described.

5. In a lifting appliance of the class described, the combination of front lifting means and rear lifting means, a shiftable member carried by the rear lifting means, a connection between said shiftable member and front lifting means, said shiftable member being arranged to be engaged and actuated by the to-be-lifted vehicle and acting on its initial movement to partially raise the front lifting means, and on its subsequent movement to fully raise the front and rear lifting means in unison, and buffer mechanism arranged adjacent said lifting means to arrest the forward movement of the vehicle, substantially as described.

6. In a lifting appliance of the class described, the combination of front lifting means and rear lifting means, means operatively connected for moving one of said lifting means by engagement of the to-be-lifted vehicle with the other of said lifting means, each lifting means embodying trunnions, 90 bearings for the trunnions, and a collar on the trunnions, and said bearings and collars being configured to limit the up and down movements of the lifting means, substantially as described.

7. In a lifting appliance of the class described, the combination of a front lifting means and rear lifting means, a lever pivotally mounted on the rear lifting means, a connection between said lever and front lifting means, said lever being shifted by engagement with the to-be-lifted vehicle and on its initial movement raising the front lifting means only, and means whereby on a subsequent movement of the lever both lifting means are moved in unison, substantially as described.

8. In a lifting appliance of the class described, the combination of a front lifting means and rear lifting means, a lever pivotally mounted on the rear lifting means, a connection between said lever and front lifting means, said lever being shifted by engagement with the to-be-lifted vehicle and on its initial movement raising the front lifting means only, a lug on the rear lifting means engaged by the to-be-lifted vehicle on a subsequent movement thereof whereby both the front and rear lifting means are moved in unison, substantially as described. 120
